POULTRY HOUSING SERVICE VEHICLE

Gerald L. Kitson, 9709 Belding Road,
Rockford, Mich. 49341

Filed July 6, 1971, Ser. No. 160,244

Term of patent 14 years

Int. Cl. D12—02

U.S. Cl. D55—1 C

FIG. 1

FIG. 2

FIG. 3

FIG. 4

FIG. 1 is a fragmented top perspective of a poultry housing service vehicle embodying my new design.

FIG. 2 is a side elevation of the poultry housing service vehicle showing the hidden side of FIG. 1.

FIG. 3 is an elevation of the poultry housing service vehicle showing the end opposite to that visible in FIG. 1.

FIG. 4 is a fragmentary bottom view of the poultry housing service vehicle of FIG. 1.

I claim:

The ornamental design for a poultry housing service vehicle, as shown and described.
